Primary Examiner — T Chase Nelson*Assistant Examiner* — Sydney Margaret Parsley(74) *Attorney, Agent, or Firm* — SANCHELIMA & ASSOCIATES, P.A.; Christian Sanchelima; Jesus Sanchelima(57) **CLAIM**

The ornamental design for a stabilizing pad for ladder feet, as shown and described.

DESCRIPTION

FIG. 1 is an isometric view of a stabilizing pad for ladder feet showing my new design;

FIG. 2 is a front elevational view thereof;

FIG. 3 is a rear elevational view thereof;

FIG. 4 is a left side elevational view thereof;

FIG. 5 is a right elevational view thereof;

FIG. 6 is a top plan view thereof; and

FIG. 7 is a bottom plan view; and,

FIG. 8 is a perspective view of the stabilizing pad for ladder feet thereof shown in condition of use, with the stabilizing pad being used in conjunction with three other broken line stabilizing pads installed onto a ladder shown also in broken lines.

The broken lines of FIGS. 1-8 illustrate portions of the stabilizing pad for ladder feet which form no part of the claimed design. The other broken lines in FIG. 8 illustrate environmental structure and additional stabilizing pads that also form no part of the claimed design.
